US0D1011426S

(12) **United States Design Patent** (10) **Patent No.:** **US D1,011,426 S**
(45) **Date of Patent:** **** Jan. 16, 2024**

(54) **REMOTE CONTROLLER**

(71) Applicant: **HTC Corporation**, Taoyuan (TW)
(72) Inventors: **Pei-Pin Huang**, Taoyuan (TW);
Chang-Hua Wei, Taoyuan (TW);
Chung-Wei Li, Taoyuan (TW); **Yu-Lin Huang**, Taoyuan (TW)
(73) Assignee: **HTC Corporation**, Taoyuan (TW)

(**) Term: **15 Years**

(21) Appl. No.: **29/764,888**

(22) Filed: **Jan. 4, 2021**

(51) **LOC (14) Cl.** **21-01**

(52) **U.S. Cl.**

USPC **D21/333**; D14/388; D14/218

(57) **CLAIM**

The ornamental design for a remote controller, as shown and described.

DESCRIPTION

FIG. 1 is a perspective view of a remote controller in accordance with our new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view of a remote controller in accordance with our new design;

FIG. 9 is a front view thereof;

FIG. 10 is a rear view thereof;

FIG. 11 is a left view thereof;

FIG. 12 is a right view thereof;

FIG. 13 is a top plan view thereof; and,

FIG. 14 is a bottom plan view thereof.

The broken lines in the drawings depict portions of the remote controller that form no part of the claim.

1 Claim, 14 Drawing Sheets
